EGG TRAY AND COVER THEREFOR
 Marvin W. Swaim, Alton, Ill., assignor to Alton Box
 Board Company, Alton, Ill., a corporation of Illinois
 Filed Mar. 15, 1962, Ser. No. 179,955
 2 Claims. (Cl. 229—51)

The object of the present invention is to provide a retail egg package which may employ a cut section of a molded pulp wholesale egg tray, although in one form of the invention individual molded pulp trays may be employed. In both cases there is a great saving in cost. When the tray is a cut section of a wholesale egg tray, very important savings in time and cost are accomplished by use of the invention. The tray, in filled condition, is associated with a cover member of unique formation because of its form and particular adaptation for the molded pulp tray section, whether the latter is for one dozen eggs or for three dozen, two dozen, one and one-half dozen.

In explanation of the above, eggs are customarily packed for wholesale distribution in boxes. These boxes hold layers of inexpensive molded pulp trays, each tray holding a plurality of dozen eggs, and upwards of three dozen eggs can be held in the pockets of the single wholesale tray. For retail distribution, it has been customary for such a box to be open and the stack trays successively emptied from their eggs, for placing in retail packages and distribution in that form of packaging, the packages generally holding one dozen eggs. The molded pulp wholesale egg trays are very inexpensive and in many cases are discarded as waste. By means of the present invention such wholesale molded pulp egg trays may not only be used, in the form of cut sections thereof for the primary element of a two piece retail package, but the egg filled trays may be taken from the wholesale box, cut into sections with the eggs still therein, and the filled sections automatically fed to a station where, by reason of special form of the second package member, the latter may be automatically applied to the tray section and bonded thereto, this being effected in rapid succession, and by dividing the wholesale pulp trays, holding eggs in their pockets, by means of such apparatus as subject of the Schwertfeger Patent No. 2,826,024.

The invention will be described with reference to the accompanying drawings, in which:

FIG. 1 is a perspective view of a closed retail egg package adapted to enclose one dozen eggs in two rows.

FIG. 2 is an end view.

FIG. 3 is a fragmentary diagrammatic view looking down toward the top of the egg tray section.

FIG. 4 is an enlarged fragmentary corner view of the structure shown in FIG. 1 showing the manner of tearing away the top wall from either of the two sealing lips to free the tuck-in holding lip of the top wall.

FIG. 5 is a fragmentary view showing the top wall moved upwardly after tearing the sealing lips.

FIG. 6 is an isometric view showing the top wall of the package swung open.

FIG. 7 is a perspective view of the molded pulp tray section. At the right hand end thereof, the position of webs extending longitudinally between the outermost posts is indicated by dotted and hatched lines, because certain cut sections of a molded pulp wholesale tray will have such outer post connecting webs only at one side thereof.

FIG. 8 is a top plan view of the blank cover member as cut and scored.

FIG. 9 is a fragmentary top plan view showing the scored margins of the longitudinal cut turned back and adhered as flanges to have mutual edge-to-edge latching abutment in the completely folded cover.

2

FIG. 10 is a view similar to the preceding figure with the flanged area of the cover folded to bring the flanges into abutment.

Referring to the drawings the invention is exemplified by a package for containing one dozen eggs. As shown in FIG. 7 the primary element of the package is a molded pulp tray which may be considered as a section cut from a wholesale pulp egg tray as shown in FIG. 2 of the said Schwertfeger patent, the ends of the pulp section shown in the drawings being cut from a wholesale pulp tray, for example, in which the ends are raised in accordance with this invention. The tray is generally indicated at 1. It is formed with egg receiving pockets as shown at 2 in two rows, each of six pockets, the pockets being separated by posts 3 connected by longitudinal webs 4, and the pockets are laterally bounded by half posts 5, because the cutting of the retail tray in the manner shown in FIG. 4 of the drawings in said Patent 2,826,024 shows such section of the outermost posts. The half posts at least one side of the pulp tray are connected longitudinally by webs 6. In FIG. 6 such webs are at both sides of the pulp tray. In FIG. 7 the said outermost webs 6 are shown only by dotted lines and hatching at the opposite side since they may be omitted.

As previously stated, the pulp end-walls of the tray are extended upwardly as indicated at 7 in the drawings. Inasmuch as normally the eggs extend upwardly somewhat above the posts 5, the end extensions rise above the posts. At their top edges each extension is thickened or otherwise formed to provide a narrow lip or abutment 7^x, for a purpose subsequently described.

In addition to the use of longitudinal webs 4 and 6, the posts are connected, in the present embodiment, by transverse webs 8. While I prefer that the tray be constructed by the pocket, post and connecting web, arrangement, illustrated in the drawings, the pockets and separation arrangement may be widely varied within the spirit of the claims annexed to this specification.

The aforesaid pulp tray has special cooperation with a very simple covering sheath, which, in the embodiment shown, is composed of a single sheet of cardboard with one fold line at 10 inwardly bounding a side wall 11, and a second fold line at 18 for a tuck-in lip 12^x, the top wall 12 lying between the two folds, and a second side wall area 14 is provided.

Reference to FIG. 8 will show the blank for the cover member. Below the tuck-in lip 12^x the blank is formed with a longitudinal cut at 20 at each end of which is a transverse cut at 21. At one side of the longitudinal cut 21 a line of scoring at 22 enables forward folding of the lower margin of lip 12^x, and its bonding by adhesive, to provide a latching flange shown in FIGS. 9 and 10 at 23. Likewise below cut 20 and between transverse cuts 21 a score line at 24 enables rearward folding of the marginal area at said score line, and its bonding by adhesive to the rear of the cover to provide a latch receiving flange 25.

At each outer side of the transverse cuts a fold-web 12^{xx} is provided and the two fold webs are bellows folded relatively to wall 14 in the manner shown at the left of FIG. 4 and in FIG. 10. Each fold web 12^{xx} is formed with a perforated tear line at 17.

In assembling the cover sheet to the pulp tray, adhesive applying rollers against which the tray is fed will apply adhesive to the side-exposed edges of the tray at the posts and also on longitudinal and outermost webs 6, FIG. 6, when they appear at one or both sides of the tray. Adhesive is applied to the fold-in margins at the opposite sides of the longitudinal cut 21 or to the cardboard area which receives them as latching flange members. The margins are folded into position as shown in FIG. 9 and adhered to provide the flanges 23 and 25. Webs 12^{xx} re-

ceive adhesive and are folded in the manner shown in FIG. 4. The side walls 11 and 14 are then adhered to the sides of the egg tray.

Care will be taken to restrict the adhesive so as to lie below the latching flange 23 of the tuck-in lip 12^x, but each web 12^{xx} will be glued onto the egg tray.

When the closed cover is to be opened, the user will pull the top wall free from the webs 12^{xx} by tearing it along the tear line 17. The tuck-in lip may then be pressed inwardly to carry flange 23 back of the overlying flange 25, and the cover pulled upwardly to the position of FIG. 6. When the desired number of eggs are withdrawn from the tray the cover may be restored to initial position and latched as shown in FIG. 4. The thickened area or flange 7^x at the top of each tray and extension preferably does not receive adhesive.

It will be understood that various modifications may be made in the elements constituting the embodiment of the invention illustrated in the drawings, without departing from the spirit of the invention.

Having described my invention, what I claim and desire to secure by Letters Patent, is as follows:

1. A cover member blank adapted for folding into a cover form for an egg-holding tray, comprising a unitary flexible member having a first longitudinal score line for defining the juncture between a first side wall and a top wall, a second longitudinal score line defining the juncture between a second side wall assembly and the top wall, two transverse cuts inwardly of the second side wall assembly and providing a web at each end of said second

side wall, a longitudinal cut intermediate the ends of said transverse cuts and extending thereto, opposed marginal areas of the second sidewall at said longitudinal cut being folded back each in a direction reversely to the other, and a tear line extending across each web area adjacent the top wall.

2. A cover member adapted for an egg-holding tray, consisting of a unitary flexible member folded longitudinally to provide a top wall, a first side wall, and a second side wall assembly, said second side wall assembly comprising an upper tuck-in lip hinged to the top wall and having its free margin folded as a flange, a second side wall member having its upper margin folded as a flange and tabs connecting said second wall member at its ends to the top wall, said tabs being separately folded to bring the members of said second sidewall into mutual face abutment and with the free edges of said flanges substantially in abutment.
